UNITED STATES PATENT OFFICE.

GEORGE T. BUDDLE, OF CHICAGO, ILLINOIS.

COMBINATION TABLE-LOCK AND OPENER.

1,103,029.

Specification of Letters Patent. Patented July 14, 1914.

Application filed June 25, 1913. Serial No. 775,824.

To all whom it may concern:

Be it known that I, GEORGE T. BUDDLE, a citizen of the United States, residing at Chicago, in the county of Cook and State of Illinois, have invented a new and useful Combination Table-Lock and Opener, of which the following is a specification.

This invention relates to improvements in extension table locks.

10 An object of the present invention is to provide a lock for an extension table the unlocking of which automatically forces the meeting portions of the table apart.

15 A further object is to provide a lock for extension tables such that the meeting portions thereof may be forced together with the result that the lock will automatically snap into a locked position.

20 A further object is to provide a lock such that any stress exerted thereon by the meeting portions of the table will be taken up by the pivot and will not tend to unlock the device.

25 With the foregoing and other objects in view which will appear as the description proceeds, the invention resides in the combination and arrangement of parts and in the details of construction hereinafter described and claimed, it being understood that 30 changes in the precise embodiment of the invention herein disclosed, can be made within the scope of what is claimed, without departing from the spirit of the invention.

35 In the drawings accompanying this specification and forming a part thereof, the preferable form of my invention is illustrated, in which:—Figure 1 is a bottom plan view of an extension table with my improved lock and opener operatively secured thereto and illustrating the same in a locked position. Fig. 2 is an enlarged view of the foregoing with my improved lock and opener in an open or unlocked position and illustrating the manner in which the adjoining 40 portions of the table are forced apart so that the fingers may be inserted between the meeting portions of the table to continue or increase the opening therebetween. Fig. 3 is a side view of the improved lock showing 45 a portion of the table in section. Fig. 4 is a cross sectional view taken on the line 4—4 of Fig. 1.

50 Referring to the drawings in which similar reference numerals designate corresponding parts throughout the several views, 5—5

are the top members which are mounted for relative movement for extension to admit the fillers therebetween as is usual in the construction of tables of the class with which my improved device is to be used, it being 60 noted in this connection that the members 5 are not provided with the usual allotment of legs and accessories in the form of braces and so forth, as the same are not essential for the clear disclosure of the present device. 65

Rigidly secured to one of the extension members 5 and preferably central thereof, is the catch plate 6 which is formed with the base plate 7 and the upstanding flange 8. The catch plate 6 provides engageable 70 means with which the latch coacts to lock the movable members 5 in juxtaposed position and at the same time affords a rigid shoulder against which the latch may push in order to move the members 5 forcibly 75 apart.

Secured to the opposite members 5 of the table taken with respect to that portion to which the catch plate is secured, is the latch generically designated 9 and which comprises a link 10 provided with a transverse notch 11 at the outer free end and which end is also provided with a beveled portion 12 which is adapted to contact with the flange 8 for the displacement of the link 10 to 80 thereby allow the said flange to come into alinement with the notch 11 which immediately springs into engagement therewith. The forward end of link 10 is pivotally secured to and guided in its movements by the 85 arm 13 the latter being provided with a slot 14 adjacent the free extremity thereof and through which extends the guide post 15 illustrated in the present drawings as of the nature of the wood screw. In order to provide for the immediate engagement of the 90 notch 11 with the flange 8 when the same come into alinement a compression U-shaped spring 16 is secured to the post 15 and to the arm 13. In order to prevent any lateral 95 play of the forward end of the link the guide member 17 is provided, the same taking the nature of an overhanging flange which is in constant or continual contact with one surface of the link 10. 100

Rigidly secured to the member 5 is a plate 18 projecting outwardly from which is the trunnion 19, the latter rotatably supporting the lever 20, the outer extremity of which is bent to form a handle 21. The 110

trunnion 19 extends through the lever 20 and is provided with a head thereon which is in the nature of a rivet and also provides a stop against which the link 10 contacts to limit the motion thereof in one direction. Pivotedly secured to the lever 20 intermediate the pivoted end and the handle is the rear end of the link 10. In order to limit the rotation of the lever 20 in a direction opposite to that limited by the trunnion 19 there is provided a stop member 22 which performs the aforementioned function.

The structure having been thus outlined the operation is as follows:—The meeting portions 5—5 of the table are brought together with the result that the flange 8 contacts with the beveled portion 12 of the link forces the same to one side and allows for the engagement of the flange in the notch 11. By bringing the actuating lever 20 into alignment with the link such as will take place when the former is rotated against the stop 22, the front edge of the notch 11 will forcibly draw or pull the two portions of the table together and rigidly hold the same in such relation. When, however, it is desired to move the portions of the table apart, the same is easily accomplished by a rotating of the actuating lever 20 away from the stop 22 with the result that the link 10 will be moved against the flange 8 and will force the two portions of the table apart for a distance slightly in excess of the length of the dowel pins which are usually used to hold the fillers or meeting portions of the table in proper relation. The advance motion of the link is limited by the same coming into contact with the trunnion 19 as it is thought will be readily appreciated. By the provision of the slot within the forward arm, it provides for the substantial rectilinear motion of the front portion of the link 10 throughout the initial movement thereof and at the same time allows for the slight sidewise displacement of the said link for the engagement of the notch and the catch plate as described. When the link reaches its extreme advanced position due to the limited length of the arm 13, the front end of the link will be drawn laterally and out of engagement with the catch plate so that a further movement of the two extension portions 5—5 of the table

may take place without further hindrance 55 from the latch.

Having thus fully described my invention what is claimed is:—

1. A lock and opener for extension tables comprising a catch plate including a flange, 60 a beveled notch-ended link, an arm pivotally secured to the notched end thereof, the remote end of said arm provided with a slot therein in engagement with a post rigidly secured to one portion of the said extension 65 table, resilient means secured to said post and said arm adapted to force the notch of said link into engagement with the flange of the said catch plate when the same are in alignment, an actuating link pivotally secured to said extension table, and pivotally engaging the link, the said pivotal connection between the link and actuating lever positioned intermediate the ends of the latter, means for limiting the rotation of said 75 actuating lever, said link adapted to hold the members of the extension table in forced contact, and to force the same apart.

2. A device of the class described comprising a catch plate, a link with means carried 80 at the end thereof adapted to engage the said catch plate for the advancement and retraction thereof when in contact therewith, a post rigidly secured to a supporting structure, an arm pivotally secured to the 85 engaging end of the said link and with the remote end thereof provided with a slot therein in engagement with said post, resilient means secured to said post and said arm forcing the engaging end of the link 90 into engagement with the said catch plate, an actuating link pivotally secured to the said supporting structure and pivotally engaging the link, said link adapted to advance and retract said catch plate when in 95 contact therewith, the said slotted arm adapted to move the said link out of engagement with the catch plate and allowing for the further advancement of said catch plate independent of said link.

In testimony that I claim the foregoing as my own, I have hereto affixed my signature in the presence of two witnesses.

GEORGE T. BUDDLE.
